UNITED STATES PATENT OFFICE.

HENRY D. HIBBARD, OF PLAINFIELD, NEW JERSEY.

FURNACE.

1,362,532.

Specification of Letters Patent.

Patented Dec. 14, 1920.

Application filed November 1, 1919. Serial No. 334,958.

To all whom it may concern:

Be it known that I, HENRY D. HIBBARD, a citizen of the United States of America, and residing at Plainfield, in the county of Union and State of New Jersey, have invented certain new and useful Improvements in Furnaces, of which the following is a specification.

My invention relates to furnaces, and particularly to puddling furnaces, the object of my invention being to provide a furnace in which the metal is not only thoroughly agitated to secure a rapid chemical reaction between the iron and the oxidizing reagents, but also mechanically worked or puddled during the operation of the furnace without the usual manipulation by hand tools now commonly practised.

In the accompanying drawings—

Figure 1 is a side elevation, partly in section, of the furnace in which my invention is embodied in one form;

Fig. 2 is a plan view thereof, partially in section on the line 2—2 of Fig. 3;

Fig. 3 is a partial end elevation of the furnace; and

Fig. 4 is a sectional view on the line 4—4 of Fig. 2.

Iron puddling is still generally carried on by the hand process, which is not only slow, but also expensive and of small output, since the operators have not the physical strength to handle batches of metal weighing over a few hundred pounds. The present apparatus provides a puddling furnace which is power driven, and by which the metal during the puddling operation is brought into intimate contact with the oxidizing slag to effect the desired chemical reaction rapidly and thoroughly, while the metal is also mechanically worked to produce a finished product more free from cinder than the usual manually formed ball, and of a size dependent only upon the capacity of the furnace.

In the form here shown the furnace proper comprises an elongated reaction vessel 5, supported in horizontal position on trunnions 6 and 7 at its opposite ends. These trunnions rest on roller bearings 8 and 9 carried by brackets 10 and 11 at the upper ends of structural pillars 12 and 13. On one or both trunnions are secured pulleys 14 and 15 engaged by suitable bands or chains 16 and 17, leading to suitable motor

means (not shown), by which an oscillatory motion is imparted to the furnace during the treatment of the metal, and a partial rotation of greater extent on the discharge of the worked charge. It will be noted that the trunnions are so located that the axis of oscillation is on one of the transverse diagonals of the furnace chamber, but to one side of the longitudinal mean center line of the furnace chamber.

The interior of the vessel 5 is subdivided by a dam 18 into a pair of pockets, wells, or containers 19 and 20, see Fig. 4, each of which is of sufficient capacity to contain the entire charge. Both pockets open to the upper portion of the chamber, which in turn communicates at its opposite ends with passages 21 and 22 through the trunnions 6 and 7, respectively. The side walls 23 and 24 of the reaction chamber are longitudinally, and the bottom transversely, arched in order the better to support the lining of the furnace. As here shown (Fig. 4), the side walls 23 and 24 of the furnace in transverse section meet at right angles at the top of the furnace, while the bottom follows an arc of 90 degrees struck from the center of oscillation 38 with the dam 18 formed by a reentrant segment midway between the ends of the arc bottom. In one of the side walls, viz., 23, is opened the charging and discharging port 25 extending substantially the length of the reaction chamber and normally closed by a door 26 hinged at 27 and fastened by latches 28. Peep holes 29 may be formed in the door to enable the operator to watch the progress of the reaction, or to introduce additional charge materials. A channel 30 may be formed centrally in the other wall 24, which forms the bottom of the chamber during the discharge of the slag through spout 31, and of the wrought metal through port 25.

The reaction between the molten pig iron and the oxidizing slag is at first exothermic, and is sufficiently energetic to maintain a suitable reaction temperature during the first part of the treatment. But after the reaction has progressed somewhat the reaction becomes endothermic, and it is necessary to provide means for maintaining the requisite temperature to the end of the treatment. Any suitable means may be provided for supplying heat to the charge as needed. Air passages 32 and 33 opening to

the hollow trunnions of the reaction chamber take heated air from the regenerators to burn the supply of fuel from burners 39 and 40 entering through apertures 37 and 5 38. Of course the fuel passes into the reaction chamber through one trunnion, and the burnt gases out through the other, the direction of the flow being controlled by an air reversing valve 36 of usual construction. 10 The ports 37 and 38 are formed through the side walls of the air passage in alignment with the trunnions 6 and 7, and oil-line nozzles 39 and 40 are introduced therethrough to supply fuel to the reaction chamber as 15 required during the treatment.

The operation of the apparatus is readily understood. Should the charge be placed cold in the furnace, the initial melt is secured by means of the oil burners and heated 20 air. Or the iron may be introduced in molten condition with an oxidizing slag or reagent, the iron and reagent being immiscible with each other. The exothermic chemical reaction which at once begins is of 25 sufficient intensity to maintain the required temperature until the carbon is freely oxidized. To carry on the reaction after the charge is introduced in the furnace, the motor is set in operation to rock the furnace 30 5 back and forth on the trunnions 6 and 7, the direction and extent of oscillation being such as to pour the charge, say from pocket 19 over the dam 18 into pocket 20, and then back again over the dam, but at all times 35 keeping it clear of the port 25, so that at no time does it lie against the door 26. Inasmuch as the oxidizing slag is of lower specific gravity than the iron, it is the first to flow over the dam, and the molten iron 40 passes down through it, thus effecting a very intimate mixture of the two and obtaining a thorough, rapid and uniform reaction in all parts of the charge. After the reaction is 45 complete, and the metal hardens into a ball or bloom, it falls over the dam from pocket 19 into pocket 20, and back again, effecting a thorough working of the metal, and by its impact squeezing out the contained slag to a much greater extent than is possible 50 with the balling manipulation by hand now commonly practised. When the bloom is completely formed the furnace is rolled over in the direction of arrow X (Fig. 4) until the side 24 of the furnace becomes the 55 bottom. The furnace is tilted sufficiently to first discharge the still molten slag through the channel 30. The bloom of wrought iron rolls down the side 24 as its inclination is increased, and passes out after 60 the slag by gravity through the port 25, pushing open the door 26, which has been unlatched in anticipation of the discharge of the furnace. Any suitable arrangement may be provided for receiving the wrought

metal and conveying it to the usual squeezers which eliminate the contained cinder. 65

It will be obvious to those skilled in the art, that the present apparatus not only expedites the reaction between the iron and its oxidizing slag, but also effects a much more uniform and complete reaction than has hitherto been obtained in the hand puddling furnaces. Furthermore, the automatic discharge of the furnace by rolling it over greatly facilitates the handling of the 75 balled metal which comes out *en masse* from the furnace in the shape of an elongated spindle, tapering to its ends, instead of as a series of relatively small balls.

I use the word "furnace" in the specification and claims to define metallurgical apparatus in which means, supplemental to the reaction heat of the charge itself, is employed to secure the temperature requisite to the desired treatment. 80

Various modifications in detail, shape, arrangement and construction will readily occur to those skilled in the art, which do not depart from what I claim as my invention. 85

I claim—

1. A metal working furnace comprising a reaction vessel having a plurality of containers or pockets, each adapted to receive and contain the charge, a dam between adjacent pockets, means for rocking the vessel to pour the charge in molten condition repeatedly from one pocket into the other and back again over the dam to promote the reaction between the elements of the charge, 95 means to heat the charge, and a door through which the metal may be discharged in solid form after the completion of the reaction. 100

2. A metal working furnace comprising a reaction vessel having a plurality of containers or pockets, each adapted to receive and contain the charge, and a door through which the vessel is charged and discharged, means for rocking the vessel to pour the 105 charge in molten condition repeatedly from one pocket into the other and back again to promote the reaction between the elements of the charge, means to heat the charge, and means to tilt the vessel in one direction to 110 discharge in succession first the slag in molten condition and then the metal in solid condition. 115

3. A metal working furnace comprising a reaction vessel having a plurality of 120 pockets, each adapted to receive the charge, means for rocking the vessel to pour the charge in molten condition repeatedly from one pocket to the other and back again, to promote the reaction between the elements of 125 the charge, a hollow trunnion on which the vessel is supported, and means for heating the charge in the reaction vessel through said

trunnion, together with a door through which the metal may be discharged in solid form by the tilting of the vessel after the completion of the reaction.

5. 4. A metallurgical furnace having a horizontally elongated reaction chamber, and a door opening in the side wall of said furnace, a door closing said opening, said door being out of contact with the charge during the reaction, and extending substantially the length of the chamber, together with means to tilt the furnace to discharge the metal through said door in solid condition after completion of the reaction.
10. 5. A metallurgical furnace having a movable reaction chamber, a door through which the treated metal may be discharged in solid form after completion of the reaction, and an independent discharge channel for the escape of the slag in fluid condition in advance of the discharge of the metal through said door.
15. 6. A metallurgical furnace having an oscillatory reaction vessel, a dam arranged in the reaction chamber, and over which the charge flows when the vessel is oscillated, an end opening to the chamber substantially coaxial with the axis of oscillation, and means for introducing fuel and air into the reaction chamber through said opening.
20. 7. A metallurgical furnace having an oscillatory reaction vessel, a dam arranged in the reaction chamber, and over which the charge flows when the vessel is oscillated, an end opening to the chamber substantially coaxial with the axis of oscillation, means for introducing fuel and air into the reaction chamber through said opening, and an associated regenerator for preheating the supply of air.
25. 8. A metallurgical furnace having an oscillating reaction chamber or vessel adapted to receive a charge of two or more immiscible molten reagents, and to mix them for the purpose of promoting chemical reactions between them by oscillating the vessel, said vessel having a door opening extending sub-

stantially the full length of said chamber and large enough to permit the discharge of the metal therethrough in one solid piece, 50 and a door therefor, said door and door opening being arranged out of contact with the charge during the period of reaction.

9. A regenerative metallurgical furnace having a hearth adapted to oscillate and revolve about an axis parallel to the center line of the furnace and provided with a dam over which the molten charge is made to flow by the oscillations, together with means for heating the charge during the furnacing 60 of the latter.

10. A regenerative metallurgical furnace having a hearth adapted to oscillate and revolve about an axis parallel to the center line of the furnace and provided with a door 65 adapted to be kept above the charge during the oscillation, but through which the charge may be evacuated when the hearth is revolved to the proper position, together with means for heating the charge during 70 the furnacing of the latter.

11. A regenerative metallurgical furnace having a hearth adapted to oscillate and revolve about an axis parallel to the center line of the furnace and provided with a dam 75 over which the charge is made to flow by the oscillations, and a door adapted to be kept above the charge during the oscillations, but through which the charge may be evacuated when the hearth is revolved to the proper 80 position, together with means for heating the charge during the furnacing of the latter.

12. A metallurgical furnace comprising a reaction vessel having two containers or pockets, each adapted to receive and contain 85 the charge, a dam between said pockets, a door suitable for discharging the vessel and extending the length of the vessel and located so as to be above the charge during the reaction, and means for oscillating and rotating said vessel.

In testimony whereof I have signed my name to this specification.

HENRY D. HIBBARD.
